UNITED STATES PATENT OFFICE.

HANS ED. THEISEN, OF MUNICH, GERMANY.

GAS-WASHING APPARATUS.

1,049,317.

Specification of Letters Patent. Patented Dec. 31, 1912.

Application filed September 26, 1912. Serial No. 722,399.

To all whom it may concern:

Be it known that I, HANS EDUARD THEISEN, a citizen of the United States of America, residing at Munich, Germany, have invented certain new and useful Improvements in Gas-Washing Apparatus, of which the following is a specification.

My invention relates generally to gas washing apparatus, and has more specific reference to a type of such apparatus where-in fixed and rotary disintegrator members are alternately arranged, and a fan or propeller blade is employed either in the same casing with the disintegrators or in a casing 15 separate therefrom.

One object of my invention is to so improve the structure of said apparatus, that a part of the casing is readily removable to give access to the interior of the device. 20 By this arrangement the principal parts of the apparatus remain secured to the floor or other foundation, while the disintegrator members, propeller blade, and appurtenant parts, usually requiring more or less frequent attention, may be taken out as a 25 whole. The arrangement referred to also greatly facilitates the assembling and disassembling of the several parts of the device.

A further object of the invention is to so 30 mount the fixed disintegrators that, while being firm and rigid when in operative position, they may be quickly and simply released from their fastenings and placed in position to be lifted out of the apparatus 35 with the revoluble disintegrators with which they alternate.

A further object of the invention is to provide the gas admission ducts or ports at such a position in the apparatus, that the 40 entering gas will immediately come into contact with the escaping water, whereby the gas, which is usually hot, is subjected to a preliminary cleaning and at the same time is freed from some of its impurities.

Other objects and advantages of the invention, as well as its detail structure and operation, will be clearly disclosed in the 45 following specification, reference being made to the accompanying drawing, where- 50 in-

Figure 1, is a vertical sectional view of a single phase gas washing machine embodying certain features of the invention; Fig. 2, is a vertical sectional view, and Fig. 3, 55 an elevational view of a modified form of

the invention as embodied in a two phase gas washing apparatus; Fig. 4, is a vertical sectional view of a further modified form of apparatus; Fig. 5, is a vertical sectional view on the line 5—5 of Fig. 4; and Figs. 60 6 and 7 are vertical sectional views of two still further modified forms of the invention.

In all forms of the invention it is proposed to provide the casing with a removable part or parts, whereby the interior of the apparatus is made readily accessible, and certain parts of the apparatus are quickly and easily removable. This general purpose is differently accomplished in certain of the different forms shown and I will now proceed to give a detail description of these several forms.

Referring first to Fig. 1, the numeral 10 denotes the apparatus casing which is firmly fixed to its foundation by any suitable means not shown, and is provided with the substantially central gas admission port 11. One of the lateral upright walls of this casing, preferably that designated 1 is removably secured to the casing proper by means of fastening means such as the nut and bolt connections 7. The wall 1 is provided with the stuffing box 2 through which passes the shaft 3 supported in the bearings 4 of the bearing block 5. The bearing block is carried by, and movable along, rails 8. At its inner end, the shaft 3 carries the disk 6 to which the revoluble disintegrator member 32 and the propeller blades 33 are secured. 80 The fixed disintegrator members are designated 60, and are carried by a supporting disk 61 fixed in the casing 10 opposite the disk 6. The washing fluid admission pipe is designated 13 and opens into a distributing cone 62 carried by the disk 6. The gas ejection passage is designated 12 and the fluid exhaust passages 14 and 15. When the apparatus is to be disassembled for any given purpose, the connections 7 are 100 loosened and the bearing block 5 moved on the guide rails 8 in the direction of arrow 9. This movement of the block 5 carries with it the wall 1, disk 6, the revoluble disintegrator members 32, fan blades 33 and the 105 distributing cone 62. The snail shaped casing 10, however, with the parts fixed thereto, remains undisturbed and secure on the foundation. In reassembling the parts, it is simply necessary to push the block 5 in a 110

direction opposite the arrow 9 until the disk 6 and wall 1 are in proper position, and secure the bolts 7 and the device will again be in operative condition.

In the form of invention illustrated in Figs. 2 and 3, an apparatus is disclosed wherein the casing 24 is centrally divided in a horizontal plane at 18, whereby the upper half of the casing is rendered removable upon release of the fastening means passing through the flanged parts 18 of the casing section. The modified form now under consideration embodies a structure wherein there are two oppositely disposed gas admission passages 16 in the lower, fixed part of the casing, there being also two sets of fixed and revoluble disintegrators 32 and 35, respectively, and two sets of propellers 33, the latter and the disintegrators being housed in the same part of the casing. The revoluble disintegrators 35 and the propeller blades 33 are carried by a centrally disposed supporting plate 34 mounted for revolution with the main shaft 63 running in the bearings 64. The fluid admission tubes are designated 13^a and discharge into the double distributor cone 62^a at substantially the central part of the casing. In this form of the invention the upper part of the casing together with the fixed and revoluble disintegrators and the propeller blades may be lifted upwardly, in the direction of arrow 17, and thus removed from the lower fixed casing section. To this end I adopt the following construction: The inner faces of the casing walls 21 are provided with the plane bearing projections 19 against which the projections 19^a formed on the rings 20 are adapted to abut. The rings 20 have the fixed disintegrator members 35 projecting therefrom into alternation with the revoluble disintegrators, and screws 22 are provided which pass through the projections 19 and 19^a to hold the rings 20 in position. Intermediate the series of securing screws 22 I provide bolts 23 the ends of which bear against the inner faces of the rings 20 and when these bolts 23 are screwed inwardly they force the rings in the same direction after the screws 22 have been loosened or removed.

To disassemble the parts of the device shown in Figs. 2 and 3 the fastenings at 18 are removed and the screws 22 loosened or removed; thereafter the bolts 23 are turned to force the rings 20 inwardly a sufficient distance to clear the shoulder or flange 25 formed within the casing on which these rings rest. The upper casing section 30 is removed and then the supporting plate 34 is raised in the direction of arrow 17 and by so lifting the plate the revoluble disintegrators fixed thereto, and the alternating disintegrators with the rings 20 are also lifted out of the casing bodily. The

lower part of the casing having the gas-admission openings 16 remains fixed to its supporting base.

In the modified form of Figs. 4 and 5 I have shown a single phase washing apparatus wherein the disintegrators are placed in a different chamber of the casing from the propeller, there being a suitable space between the outer surfaces of the two casing parts. In this form of the invention the casing is centrally divided in a horizontal plane at 18 and has the gas admission passage 16^a in its lower part. The disintegrators are housed in the casing section 24' while the fan or propeller 33' is housed in the casing section 26. The inner wall 21' of the casing section 24' is provided with a plane bearing surface 19' against which the ring 20' carrying the fixed disintegrator members 35' bears. Mounted upon the shaft 63' is the propeller blade 33' in the casing section 26 and the drum 34' carrying the revoluble disintegrators 32' in the casing section 24'. The inner part of the casing section 24' is also provided with the supporting and positioning shoulder 25' for the rings 20'. Between the casing sections 24' and 26 is a suitable space 27 to permit of manipulating the screws 22 and bolts 23, in the manner above described in connection with Figs. 2 and 3 of the drawing. By providing the gas inlets 16 at the lower part of the fixed casing section, as shown in certain figures of the drawings, the very great advantage is obtained that the main part of the impure raw gas meets the outflowing water or other cleaning fluid employed. The result of this is that the gas is partly freed of its contained impurities immediately after it enters the apparatus, and moreover the water acts to cool the gas, which is usually hot as it flows into the device. The gas, in the main, passes through the annular chamber 30 without any appreciable quantity flowing into the intermediate space. The function of the chamber 30 is to proportion the entering uncleaned gas to the outflowing body of water, thus enhancing the cleaning and cooling action on the gas at its entrance into the lower part of the device.

The assembling and disassembling of parts of the device shown in Figs. 4 and 5 are effected in the same manner as described in reference to Figs. 2 and 3, and an additional description is deemed unnecessary.

The device shown in Fig. 6 is similar in principle and construction to the device of Figs. 4 and 5, the main difference being that the gas entering the admission port 16^b must pass the right hand disintegrator members 32^b 35^b at mid current and it then passes through the left hand disintegrator section 32^b 35^b in a direction opposite that in which the washing fluid therein flows. The parts 133

in this figure are similar to those of Figs. 4 and 5 and having been designated with like reference characters using the exponent 2 thereafter.

5 Referring to Fig. 7, I have here shown a form of apparatus wherein two disintegrator sections are symmetrically arranged at the sides of a centrally disposed propeller blade 33³. In this and certain of the 10 other forms of the device the propeller is shown as open at the sides and having its ends inturned at 38. The device of Fig. 7, is, in effect, a multiple cleaner embodying 15 the features of the construction of Figs. 4 and 5. It has two gas admission passages 16⁶, and two counter current disintegrator sections 32³ and 35³. The parts 38 of the propeller act as pressure blades while the parts 39 act as washing members and wash 20 the gas against the conical washing surfaces 40 of the casing. One or more drain passages or tubes 37 may be provided for the fluid and impurities as shown in the drawing. The form of invention including a propeller blade open at the sides and closed at 25 the ends, in combination with a conical washing surface and a drain 37 serves to hurl the washing fluid taken up by the gas, against the conical surface 40 and to carry 30 off the fluid through the drain, whereby a fluid separator directly behind the gas exit may be dispensed with.

The operation of the several forms of my 35 invention shown and described in the drawings is substantially the same. The gas to be cleaned enters the apparatus through the several inlets and is subjected to the action of the sprays or jets of water whereby the gas is cooled and cleaned. The rotating disintegrator members agitate the gas and by 40 centrifugal action the heavy particles are thrown outwardly and pass out from the apparatus with the water. Cleaned gas is carried off by means of the propellers and 45 the outlet pipes for the gas to suitable storage tanks, or to any other place where it is desired to conduct the gas.

I have herein shown and described my invention in considerable detail, but I wish it 50 to be understood that the invention is susceptible of material modification and variation without departing from the spirit of the invention as defined by the scope of the appended claims.

55 I claim:

1. A gas washing apparatus, embodying 60 therein a casing having a removable section, relatively fixed disintegrator members with in the casing revolvably mounted disintegrator members therein, and means for releasing the fixed disintegrator member from the casing whereby said disintegrator members may be removed as a unit with said removable section.

65 2. A gas washing apparatus embodying

therein a casing, having fixed and removable sections, stationary disintegrator members secured within the casing, rotary disintegrator members within the casing, said rotary disintegrator members interlacing 70 with the fixed disintegrator members, releasable means for securing the removable section of the casing to the fixed section, and means for releasing the stationary disintegrator members from the casing to permit of the rotary and stationary disintegrator members being removed from the casing as 75 a unit.

3. A gas washing apparatus, embodying 80 therein a casing provided interiorly with plane bearing surfaces, rings adapted to contact with said bearing surfaces, fixed disintegrators carried by said rings, means for removably securing said rings against said bearing surfaces, and means for forcing said rings inwardly of the apparatus away from 85 said bearing surface.

4. A gas washing apparatus embodying 90 therein a casing provided interiorly with plane bearing surfaces, rings adapted to contact with said bearing surfaces, fixed disintegrators carried by said rings, screws passing through said bearings and into the rings for retaining the latter in fixed position, and bolts passing through said casing 95 and having their ends abutting said rings whereby inward movement of said bolts will force said rings inwardly away from the bearing surfaces.

5. A gas washing apparatus embodying 100 therein a casing having a plurality of spaced chambers, the walls of which are connected by narrow necks, disintegrator members within the chambers of the casing, and means accessible from the spaces between the 105 chambers to fasten the disintegrator members in position in the casing.

6. A gas washing apparatus embodying 110 therein a casing divided into a plurality of adjacent sections having a space therebetween, gas washing means in one of said sections, a propeller blade revolvable in the other of said sections, and means projecting into said space whereby said gas washing means may be forced into the casing section 115 wherein the same is housed.

7. A gas washing apparatus comprising a 120 divided casing, one portion of the casing being removable and the other portion being fixed, means for detachably securing the removable portion of the casing to the fixed portion, a rotary disintegrating member supported by the removable portion of the casing, and a movable supporting means for the removable portion of the casing and the 125 rotary disintegrating member supported thereby whereby the removable portion of the casing and the disintegrating member may be removed from the fixed portion of the casing.

8. A gas washing machine comprising a casing having a fixed portion and a removable portion, stationary disintegrator members secured to the fixed portion, rotary disintegrator members supported by the removable portion and adapted to interlace with the stationary disintegrator members, and means to remove the removable portion of the casing from the fixed portion and to withdraw the rotary disintegrator members

supported thereby from their interlaced position with the stationary disintegrator members.

In testimony whereof I have affixed my signature in presence of two witnesses.

HANS ED. THEISEN.
